(57) **CLAIM**

The ornamental design for icons for display section of communication device, as shown and described.

DESCRIPTION

The single FIGURE is a front view of a set of icons for a display section of a communication device showing our new design, the broken line drawing of a communication device is for illustrative purposes only and forms no part of the claimed design.

1 Claim, 1 Drawing Sheet

UNITED STATES PATENT AND TRADEMARK OFFICE
CERTIFICATE OF CORRECTION

PATENT NO. : Des. 495,340 S
DATED : August 31, 2004
INVENTOR(S) : Fumiyoshi Toyoshima et al.

Page 1 of 3

It is certified that error appears in the above-identified patent and that said Letters Patent is hereby corrected as shown below:

The title page showing illustrative figure, should be deleted and substitute therefor the attached title page.

Delete Fig 1 Drawing sheet and substitute therefor the Drawing sheet consisting of Fig 1 as shown on attached page.

Title page.

Item [54], Title, insert -- **SET OF** -- before "ICONS".

Signed and Sealed this

Twenty-third Day of August, 2005

A handwritten signature in black ink, appearing to read "Jon W. Dudas", is centered on a dotted rectangular background.
